LATCHING CONSTRUCTION

Edwin Klahn, New York, N. Y., assignor to Adolf C. Blechner, New York, N. Y.

Application November 21, 1938, Serial No. 241,568

1 Claim. (Cl. 70—63)

The present invention relates to a latching mechanism.

It is among the objects of the present invention to provide an improved latching arrangement and particularly an improved latching arrangement designed to be utilized in connection with various devices, as for example, for banks, for stands to receive and lock liquor or perfume bottles and so forth, which will be durable and reliable and of inexpensive construction and yet will not be subject to ready derangement or tampering by the persons to whom such bank may be given.

Other objects will be obvious or will appear during the course of the following specification.

In accomplishing the above objects, it has been found most suitable to provide a stand with a double or removable bottom, said bottom having a double wall construction between which is contained two reciprocal locking elements. These locking elements are desirably spring biased so as normally to project outwardly from the enclosure of the double bottom and engage openings in the lower edges of the side walls of the bank.

An opening is provided in the double wall construction permitting insertion of a relatively simple key construction by which the reciprocal members may be withdrawn from the openings in the side walls of the banking casing permitting the bottom to be withdrawn.

The key is preferably of a construction having rounded sides which will operate the reciprocal elements and yet is not similar to readily available instruments by which the device could be unlatched by the possessor thereof.

Although the reciprocal latch element may take various forms, it has been found most satisfactory in one form of the invention to provide closely fitting offset bars having extensions or lugs adjacent the key opening which are designed to engage the key when the bars are to be withdrawn.

These bars may be formed of a relatively thin resilient sheet metal.

The above and other objects will appear more clearly from the following detailed description when taken in connection with the accompanying drawing, will illustrate a preferred embodiment of the inventive idea.

Referring to the drawing:

Figure 1 is a front elevational view of the bank construction.

Figure 2 is a transverse sectional view upon the line 2—2 of Figure 1 upon enlarged scale as compared to Figure 1.

Figure 3 is a transverse sectional view of the

bottom and lower portion of the casing upon the line 3—3 of Figure 2.

Figure 4 is a detailed fragmentary sectional view showing the cooperation of the key and latch construction.

Figure 5 is a detailed side sectional view upon the lines 5—5 of Figure 4.

Figures 6 and 7 are detailed side sectional views upon the lines 6—6 and 7—7 of Figure 2 upon enlarged scale as compared to Figure 2 showing the manner of mounting and guiding the bottom plate elements.

Figure 8 is a perspective view of the key shown in location in the dot and dash lines in Figures 2 to 5.

Referring to the construction of Figures 1 to 7, the bank consists of a casing having a removable double bottom or base B, a reciprocating locking arrangement including the two bars C and a key element D.

The casing A is provided with the coin slot 10 and the side walls 11, the lower ends of the slotted walls are provided with slots 12 (see Figures 2 and 3).

The base B is provided with an upper bottom 13 and a lower bottom 14 between which are positioned the reciprocating strips or bars C.

The upper and lower bottoms 13 and 14 are held together, as best shown in Figure 7, by the upturned flange 15 extending through the opening 17 in the upper bottom 13, which flange 15 has a down turned portion 16 engaging the edges of said opening as indicated at 18.

The edges of the upper bottom element 13 are turned down as indicated at 19 and they are slotted, as indicated at 20, to coincide with the openings 12.

The base or lower bottom plate 14 has the down turned portions 21 which fit inside of the lower edges 22 of the side walls 11.

The outturned flange 23 is designed to contact with the table or other support upon which the bank is placed and the upturned portions 24 are designed to contact at their upper ends 24a with the side walls 11.

The locking bars C are made of thin sheet metal and are preferably resilient and they each have an inside end 26a, which is substantially offset from the outside ends 25. The offset ends 25 are provided with inturned end portions 26 which project through the openings 12—20.

The portions 26a of the bars C are provided with the lugs 27 which are positioned at each side of the openings 28 in the upper bottom plate 13 and 29 in the lower bottom plate 14.

The opening 28 in the upper plate 13 receives the rounded end portion 30 of the key D of Figure 8 while the lower opening receives the enlarged portion 31 having the rounded edges 32.

The upper portion 33 of the enlarged portion 31 is designed to contact the lower faces of the edges 34 of the opening 28, as best shown in Figure 5.

The offset portions 25 of the bars are provided with notches 35 to receive the ends 36 of the spring 37, said spring having turned portion 38, which is riveted at 39 to the bottom plate 14.

The bent ends 36 of the spring as shown in Figure 2, tend to press the ends 26 of the bars C outwardly into the recesses 12-20.

As shown in Figure 6, the upper plate 13 also has stamped out and down turned portions 40, the lower ends 41 of which touch the bottom plate 14 and guide the side edges of the bars 25.

The offset ends of the bars are guided by the openings 12-20 so that the bars C will be held in predetermined position.

In operation the key D will be inserted in the opening 29, as shown in Figures 3 and 5, with its tip portion 39 projecting into the smaller opening 28 in the upper plate 13.

When the key is inserted into the position shown in Figure 3, with the shoulders 33 abutting the edges 34 of the upper plate 13 adjacent the key hole, and turned to the position indicated in Figures 4 and 5 it will press the projecting portions 27 apart and withdraw the end portions 26 from the openings 12 and 20. This motion will be stopped by the contact, as indicated at 45 in Figure 4.

It is apparent that the construction shown is quite simple, rugged and not readily susceptible to being tampered with or broken. It also is quite durable and will stand up for long periods of time without derangement and at the same time, can be operated by the bank with the maximum of convenience.

It will be noted that a particularly valuable feature of the present invention is that as soon as the key is removed, the bars C will snap back into projected position where they will either lock the bank in position on the base or project beyond the walls 11 if the base is not in position.

It would also be possible to place the inturned portions 26 in the side walls 11.

Although a bank is shown as the preferred utilization of the bottom latch construction, it is obvious that the construction, as shown in Figures 2 to 5, might be applied to perfume bottle or liquor bottle stands and to various other devices which are to be locked to prevent unauthorized usage of the contents thereof or intrusion into the interior thereof.

Furthermore, the double plate locking device, as shown, may also be utilized at the top or sides of an enclosure or stand as well as the bottom, as shown.

It is apparent that the specific illustrations shown above have been given by way of illustration and not by way of limitation and that the structures above described are subject to wide variation and modification without departing from the scope or intent of the invention, all of which variations and modifications are to be included within the scope of the present invention.

What is claimed is:

A lock comprising a double plate flat carrier, two flat bars in said carrier having aligned locking portions and offset parallel overlapping unlatching portions, said last mentioned portions having transversely projecting legs extending toward each other from the sides adjacent the aligned portions to engage a key on opposite sides of the key, the ends of the carrier having recesses for said aligned portions, said aligned portions being notched and a flat U-shaped spring engaging said notches to press said aligned portions apart.

EDWIN KLAHN.
